BRACELET CLASP

David Block, Philadelphia, Pa.

Application September 5, 1945, Serial No. 614,551

1 Claim. (Cl. 24—68)

1

This invention relates to improvements in bracelet clasps of the type used on wrist-watches, wrist-bands and the like.

A principal object of the invention is to provide a clasp comprising releasable spring-actuated means for opening and extending the clasp to facilitate removal of the bracelet from or placement thereof on the wrist.

Another object of the invention is to provide clasp-opening means that will function with a minimum of effort on the part of the operator, and which at the same time will be both safe and efficient. This objective contemplates the avoidance of defects in the prior art structures, wherein the means for extending the clasp have been both complicated and cumbersome.

A further object of the invention is to provide a clasp having extension means which will be compact so as to fit snugly within a relatively small casing, thereby affording a neat and pleasing appearance on the wearer's wrist.

A still further object of the invention is the provision of means whereby the extensible members of the clasp may be simultaneously ejected from said clasp casing on release of a spring detent member, thereby affording a quick action and avoiding delays incident to the conventional manual manipulation.

Still another object of the invention is to provide a clasp that is readily serviceable and one that may be repaired with a minimum of trouble and expense.

Yet another object of the invention is to provide novel means whereby the bracelet may be adjusted to suit the wearer's wrist.

The above and other objects will more clearly appear from the following detailed description of the device, with particular reference to the accompanying drawings, in which:

Fig. 1 is a side elevational view of the device;

Fig. 2 is a plan view, showing the device with the cover of the casing removed with part of the spring not shown;

Fig. 3 is a longitudinal sectional view on the line 3—3, Fig. 2, showing the clasp in its closed position;

Fig. 4 is a transverse sectional view taken on the line 4—4, Fig. 2;

Fig. 5 is a perspective view showing the clasp in extended position;

Fig. 6 is a perspective view of one of the sliding links; and

Fig. 7 is a perspective view of the detent member.

Referring now to the drawings in detail, Fig. 1

2

shows an outer link casing 1 comprising a body portion 1a, a cover portion 1b, and a base portion 1c, said cover portion being pivotally attached to one end of the casing portion 1a, as at 3, and held in a closed position at the opposite end by a resilient catch 3a so as to permit the raising of the cover 1b conveniently for repair and adjustment of certain mechanism contained in the casing body 1a.

One end of the casing body 1a has, as a part thereof, hinge means 5 for attaching the casing to one end of a wrist-band or bracelet X, while the opposite end of the casing is open, as at 5a, to permit extensible links 6, 7 and 8, which are slidably mounted therein, to be projected therefrom and returned thereto.

Within the body portion 1a of the casing 1 is a shelf 9 which extends the length of the casing with respect to the side and end walls of the body portion 1a of the casing 1.

The shelf 9 supports a spring member 10 having its one end attached to one end of the casing by means of a hook 10a formed at the end of the spring, and having its opposite end 10b attached as, by hooking, to a pin member 6a which projects from the link 6 through an elongated slot 11 formed in the shelf 9, up into the space in the casing 1 in which the spring 10 is mounted, above said shelf 9.

The extensible link members 6, 7 and 8 slidably fit within the casing 1, beneath the shelf 9, in an adjacent parallel nesting relation to each other. The middle link 7 consists of a solid piece of material, preferably a thin sheet of resilient metal, having at its one end an upwardly extending pin member 12 and at its other end a downwardly extending pin member 13. The upwardly extending pin member 12 slidably fits within an elongated slot 14 formed in the extensible link 6, said pin abutting the end edge of said slot when the links are in a closed position within the clasp. The downwardly extending pin member 13 slidably fits within an elongated slot 15 in the extensible link 8, and, when the links are in closed position, abuts one end edge of the said slot 15 in the link 8. The link member 8 is adapted to slide on a pair of laterally spaced bearing surfaces 23, 23 formed in the upper side of the base element 1c, with a longitudinal channel 24 between said slideways 23, 23.

Referring further to said link member 8, at one end thereof and on its under surface are a plurality of adjusting notches 16, which are arranged to cooperate with a spring detent member 17 forming a lock for holding the nested links 6—7—8

55

in closed position. At the other end of said link member 8, is a rivet or other suitable attaching means for joining the link 8 to the second end X' of the bracelet or wrist-band.

The spring detent member 17 may be of any suitable resilient material and comprises foot portions 18 and 19, which are slidably mounted within the longitudinal channel 24 formed in the base member 1c of the casing. The foot portions 18 and 19 are connected to a central catch portion 25 of the detent 17 by oppositely sloping leg portions 20 and 21. Extending laterally from opposite sides respectively of the catch 25 are arms 26, 26 which are provided at their outer ends with finger gripping pads 22, 22, which when gripped and pressed downwardly cause the resilient legs 20 and 21, of the detent 17 to flatten out on the floor of the channel 24, thereby releasing the latch or catch 25 of the detent 17 from the notches 16 of the link 8. The side walls of the body portion 1a of the casing 1, and the slideways 23, 23 for the link 8, as formed in the base member 1c are vertically slotted at 27, 27, to accommodate the vertical movements of the legs 26, 26 of the detent 17.

In operation the device functions as follows:

When the bracelet is closed, all of the extensible elements 6—7—8 of the clasp are contained and retained within the casing 1. The spring member 10, at that time is extended the length of the casing 1, due to the pull applied thereto by the pin member 6a of link 6, which has been pushed into the casing and to which pin one end of said spring member 10 is attached, as above described. The spring 10 is therefore under tension. In such closed position, the upwardly extending pin member 12 of link 7 abuts one end edge of slot 14 of the link 8, thereby retaining said link 6 in its closed position. The downwardly extending pin member 13 of the link 7 abuts the one end of the slot 15 of link 8, and thus retains the link 7 in its closed position. The link member 8 is retained in its closed position by the catch portion 25 of the spring detent member 17, which fits into the notches 16 of the link 8 as described. Thus, in the closed position the entire linkage 6—7—8 is nested or collapsed and retained in locked relationship within the casing 1, each member with respect to the other.

When it is desired to open the clasp, the wearer merely exerts inward pressure upon the finger pads 22, 22, and presses said pads downwardly so that the catch 25 of the spring detent member 17 will be released from the notches 16 of the link 8. The moment this release occurs, the spring member 10 is free to contract and in so doing will carry with it the pin member 6a to which one end of said spring is attached, as above described. The said pin member 6a, functioning as an integral part of the link 6, will slide along the slot 11 of the shelf 9, continuing to so move until the pin 6a abuts the other end edge of the slot 11.

As such movement of the link 6 and pin 6a takes place, the pin member 12, which abuts the one end of the slot 14 of link 6, is also moved along the slot 14, carrying with it the link 7 of which the pin member 12 functions as an integral part. Also, as link 7 moves longitudinally, it carries with it the downwardly extending pin member 13 which abuts the one end of the slot 15 of link 8, so that the link 8 is longitudinally projected.

At this point in the extention of the bracelet, all of the link members 6, 7 and 8 lie outside of the clasp casing adjacent and parallel to each other. From this position, resulting from the release of the spring member 10, further extension is permitted by the slots 14 and 15. To this end, longitudinal tension is applied to the links 7 and 8, whereby link 7 will be extended the length of the slot 14, as the pin member 12 of this link slides therealong, and the link 8 will slide outwardly from the clasp to an extent permitted by its slot 15. The clasp is now at its full extended length, and may readily be placed upon or removed from the wrist.

To close the clasp, manual longitudinal pressure is exerted upon the extended links 6, 7 and 8 to force them towards and into the casing 1, until the spring detent 17 again cooperates with the desired notch 16 in the link 8 to retain said clasp in its contracted position.

It is to be noted that the bracelet may be adjusted as to circumference while in the contracted state, to some minor extent, by means of the series of notches 16 in the underside of link 8. Thus, a slight expansion being desired, the spring detent may be released and the links allowed to move until the detent passes into the desired notch. Such extension involves a movement of the links as a unit while in the adjacent and parallel relation, so that no unattractive appearance results. This feature of simultaneous extension of the links is a highly important feature of the invention.

I claim:

35. An extensible bracelet clasp comprising a casing including a base, a top, and a longitudinally slotted shelf intermediate and substantially parallel to said top and said base and forming upper and lower spaces between said top and said shelf and said base, a spring member in said upper space with one end attached to said casing, a series of relatively slideable link members nested in said lower space, a pin on one end of one of said link members extending through the slot in said shelf and into said upper space and attached to the opposite end of said spring, said link member having a longitudinal slot formed therein, a solid link member underlying the first said link member, a pin in one end of said solid link extending into the longitudinal slot of the first said link member, a longitudinally slotted link member underlying said solid link member, a second pin at the opposite end of said solid link member extending into the longitudinal slot of the third said link member, and means comprising a catch member constructed and arranged to engage one of a plurality of notches in said third link member for retaining said nested link members in a collapsed locked relationship within the casing against projection therefrom by said spring.
